EXPANDED-METAL STRUCTURE

Application filed August 8, 1927. Serial No. 211,311.

The present invention relates to expanded metal structures.

The present application is a continuation as to common subject matter of applicant's copending application Serial No. 118,206, filed June 24, 1926, for improvements in expanded metal structures, certain of the subject matter of the present application being divisional subject matter divided out of said copending application.

An object of the present invention is to provide an improved expanded metal structure well adapted to meet the requirements of commercial operation which requirements have formerly been met by relatively expensive and relatively heavy fabricated structures.

Further objects will appear as the description proceeds.

20 Referring to the drawings:

Figure 1 shows in side elevation a commercial rolled shape, an I-beam being chosen for illustration, said commercial rolled shape being provided with transverse slits which illustrate an initial operation in the treatment of said commercial shape according to the present invention;

25 Figures 2 and 3 are views similar to Figure 1 but showing the rolled shape after subsequent slitting operations have been performed thereon;

Figure 4 is a top plan view of the structure shown in Figures 1 to 3, but after a swedging operation has been performed thereon, and showing a die in position to perform its swedging operation;

30 Figure 5 is a sectional view taken along the plane indicated by the arrows 5-5 of Figure 4;

Figure 6 is a view in side elevation of a structural steel member in completed form, which structural steel member results from further treatment of the member as shown in Figures 4 and 5;

40 Figure 7 is a sectional view taken along the plane indicated by the arrows 7-7 of Figure 6;

45 Figure 8 shows in side elevation another commercial rolled shape, an angle being chosen for illustration, a wall or flange of

said angle being provided with apertures illustrating an initial operation in the treatment of said angle according to the present invention;

50 Figure 9 is an end view of the structure shown in Figure 8;

Figure 10 is a view similar to Figure 9 but showing certain of the apertures referred to in connection with Figure 8 connected by longitudinally extending slits;

55 Figure 11 is an end view of the structure shown in Figure 10 but showing one of the walls of the angle swedged transversely;

Figure 12 is an end view showing a transversely swedged portion in an intermediate stage of the operation for swinging said transversely swedged portion from the position illustrated in Figure 11 to the position illustrated in Figure 13;

60 Figure 13 is an end view of the angle with the swedged portions returned to the positions which they occupy in service;

Figure 14 is a side view of the structure shown in Figure 13;

65 Figure 15 is a fabricated structure made up of structural steel members such as illustrated in Figures 13 and 14; and

Figure 16 is a sectional view taken along the plane indicated by the arrows 16-16 of Figure 15.

70 As noted above, an I-beam has been chosen for illustrating the invention in Figures 1 to 7. An I-beam of standard design is indicated by the numeral 10, the web 11 of which I-beam is provided with transversely disposed slits 12-12 extending part way across said web, symmetrically of said web, which slits are arranged in pairs, said pairs being preferably equi-spaced along a mid portion of the length of the I-beam. Arranged symmetrically with reference to the pairs of slits 12-12 are other sets of transverse slits 13-13, said slits 13-13 being arranged in sets of four. The outer extremities of the slits 12-12 are 75 preferably disposed along lines 14-14 arranged parallel with the axis of the I-beam 10. The outer extremities of the slits 13-13 are disposed along parallel lines 15-15, which are also substantially parallel with 80

85 the outer extremities of the slits 12-12.

85 Figure 4 shows the I-beam 10 with the slits 12-12 and 13-13 in their initial positions. The slits 12-12 are disposed in pairs, said pairs being equi-spaced along a mid portion of the length of the I-beam 10. The outer extremities of the slits 12-12 are 90 preferably disposed along lines 14-14 arranged parallel with the axis of the I-beam 10. The outer extremities of the slits 13-13 are disposed along parallel lines 15-15, which are also substantially parallel with 95 the outer extremities of the slits 12-12. The slits 12-12 and 13-13 are disposed in pairs, said pairs being equi-spaced along a mid portion of the length of the I-beam 10. The outer extremities of the slits 12-12 are 100 preferably disposed along lines 14-14 arranged parallel with the axis of the I-beam 10. The outer extremities of the slits 13-13 are disposed along parallel lines 15-15, which are also substantially parallel with the outer extremities of the slits 12-12.

the axis of the I-beam 10. The inner extremities of the slits 13-13 are defined by the lines 14-14. Those slits 13-13 disposed at the two extremities of the slotted portion of the I-beam 10 may be elongated to communicate with each other to form the elongated slits indicated by the numeral 16.

In addition to the transverse slits 12-12 and 13-13, the I-beam is provided with the longitudinally extending slits 17, which slits 17 are disposed along the axis of the I-beam, being disposed in position to connect the mid point of one of the pair of slits 12 to one of the next adjacent pair of slits 12. The outer extremities of slits 13-13 are connected by longitudinally extending slits 18, said longitudinal slits 18-18 being disposed in position connecting slits of one set of slits 13 to slits of the next adjacent set of slits 13. The slits 18-18 are disposed in overlapping relationship with the slits 17, thereby providing ribbons or lacings which may be swedged from the plane of the web 11 to provide an expanded metal structure.

By reason of the arrangement of slits as above described, a plurality of lacings 19 are provided, separated by portions 20-20, which will be referred to herein as intact, 30 said intact being defined by the slits 12-12.

It will be noted that the outer slits 18-18 are disposed in pairs, their intact 20-20 being directly opposite each other. The intact between the slits 17-17 are disposed 25 midway between the intact of said slits 18-18. The slits 13-13 are of substantially half the length of the slits 12-12.

The I-beam 10, slotted as above described, is subjected to a swedging operation, a 40 wedge-shaped tool 21 being provided to deform the lacings, as shown in Figures 4 and 5. In practice, the cutting of the slits 18 and the deforming of the lacings are performed in the same operation, the tool 21 45 having a width equal to the distance between said slits 18. The semi-completed structure shown in Figures 4 and 5 is then subjected to a pulling or drawing operation, the two flanges of the I-beam being 50 pulled directly away from each other; or, if preferred, pushing force in the direction of the arrows in Figures 4 and 5 may be applied to spread the flanges; or a combination of said pulling and pushing forces may 55 be employed, so long as a resultant component of material value is applied in the original plane of the web 11. The act of separating the two flanges of the I-beam 10 will naturally tend to pull the deformed 60 lacings 19-19 back to positions symmetrical with the web of the I-beam. In order to do that, however, said lacings must turn at right angles to said web (that is, at right angles to their original plane), so that the 65 final expanded product will have the shape

shown in plan and in cross section in Figures 6 and 7, respectively, the center joint or intact being a U-shaped cross section on the intact 20-20. As appears in Figure 6, the lacings form intersecting diagonals, providing a diamond-shaped conformation. 70

The structure shown in Figure 6 takes the form of a beam, said structure being illustrated as having the lower half of its end portions swedged upwardly into engagement with the upper half thereof; this arrangement being advantageous when the structure is to be used as a beam. If preferred, reinforcing members 22, such as tubing, may be disposed between and preferably welded to the upper and lower portions of the structure. Though Figure 6 illustrates a beam, it will be clear that the invention is equally applicable to columns, 80 diagonals and other structural members. 85

Referring now to Figures 8 to 16, inclusive, an angle of commercial design is chosen for illustrating the invention. The two walls or flanges of a commercial angle are indicated by the numerals 23-23. Operations upon one of said walls 23-23 will be described in detail, it being understood that similar operations may be performed upon the other wall or flange 23. The numerals 24-24 indicate apertures which may conveniently take the form of squares, said apertures being disposed in groups longitudinally of the corresponding wall or flanges 23. Said apertures 24-24 are disposed midway of the width of their corresponding flange, and preferably are of the same size and equi-distant from the edge of the flange. Pairs of said apertures 24-24 are relatively close together, said pairs being spaced apart at predetermined distances along the structural steel member. Arranged symmetrical 100 with each pair of adjacent apertures 24 is a notch 25 located in the edge of the corresponding wall 23. One of the apertures 24 in each pair of adjacent apertures is connected with the next aperture of the neighboring pair of adjacent apertures by means of slits 26. Said slits 26-26 are in line with one another, being separated by the intact 27-27. Symmetrically disposed in the space between each slit 26 and the edge of the corresponding flange or wall 23 is an aperture 28 which may be used as a rivet hole in providing a fabricated structure shown in Figures 15 and 16. The slits 26-26 provide lacings, which lacings are indicated by the numerals 29, and said lacings according to the present invention are swedged transversely of the corresponding wall 23 to take the angular form illustrated in Figures 11 and 14, the swedging force being applied symmetrically of said lacings 29-29 and being applied in such a manner as to leave flat portions 30-30 intermediate of the length of said lacings 29. 110 115 120 125 130

A distorting force is then applied to the structural steel shape to swing the swedged lacings 29 out of a position at right angles with the corresponding wall 23 into a position symmetrical with said corresponding wall 23. Figure 12 shows an intermediate position of a lacing 29 in the swinging movement referred to. Figure 13 shows the final position of the lacing 29 relative to the corresponding wall 23. The notches 25 aid in permitting the swinging action referred to with a minimum of destructive stresses within the metal of the structural steel shape. The strips of lacings 29 have faces which are relatively broad compared to the thickness thereof. The short axes of said broad faces, as the parts are viewed in Figures 13 and 14, are normal to the wall 23 from which they are swedged.

Though the above description has been outlined with reference to only one wall or flange 23 of the structural steel member, it will be understood, of course, that the other wall may be similarly treated.

Figures 15 and 16 illustrate a fabricated structure made up of four angles, both walls of which have been treated in the manner above described. Corresponding flats 30-30 of two structural steel members which have been treated as above described are placed in contact with one another and riveted or otherwise secured together by suitable holding means 31.

By reason of the present invention a method is provided whereby expanded metal structures may be manufactured from commercial rolled shapes which expanded metal structures will have decided advantages in a commercial sense.

Though two embodiments of the present invention have been chosen for purposes of illustration, it will be understood that many modifications may be made without departing from the scope of the invention. It is intended to cover all such modifications that fall within the scope of the appended claims.

What is claimed is—

1. An expanded metal structure comprising an integral member having flanges upon the two opposite sides thereof, web portions contiguous to said flanges, and diagonals connecting said web portions, said diagonals intersecting one another to form diamond shapes, said diagonals being disposed in planes normal to the plane of said web portions.

2. An expanded metal structure comprising an integral member having opposite flanges, web portions disposed adjacent to said flanges and in right angular relationship therewith, and intersecting diagonals arranged in diamond-shaped conformation, said diagonals being disposed in planes in

right angular relationship to said web portions.

3. An expanded metal structure comprising an integral member including a web portion having openings within the boundaries of said web portion, said openings being defined by diagonally intersecting members, said members being disposed in planes at right angles to the plane of said web portion.

4. An expanded metal structure comprising an integral member including a web portion having openings within the boundaries of said web portion, said openings being defined by diagonally intersecting members, said members being disposed in planes at right angles to the plane of said web portion, the intersections of said intersecting members being flat portions disposed in substantially the same plane as said web portion.

5. An expanded metal structure comprising an integral member having a flat wall portion and pairs of diagonal strips connected to each other and directly connected to said wall portion, said strips having wide faces relative to the thickness of said strips, the short axes of said wide faces being normal to said wall portion.

6. An expanded metal structure comprising an integral member having a flat wall portion and pairs of diagonal strips connected to each other and to said wall portion, said strips having wide faces relative to the thickness of said strips, the short axes of said wide faces being normal to said wall portion, each of said diagonal strips being disposed symmetrically with reference to the plane of said wall portion.

7. An expanded metal structure comprising an integral member including a flat wall portion and a plurality of lacings swedged from said wall portion, each of said lacings including a pair of strips connected to each other and directly connected to said wall portion, said strips having wide faces relative to the thickness of said strips, the short axes of said wide faces being normal to said wall portion.

8. An expanded metal structure comprising an integral member including a flat wall portion and a plurality of lacings swedged from said wall portion, each of said lacings including a pair of strips connected to each other and to said wall portion, said strips having wide faces relative to the thickness of said strips, the short axes of said wide faces being normal to said wall portion, each of said strips being disposed symmetrically with reference to the plane of said wall portion.

9. A beam comprising an expanded metal structure, said expanded metal structure being an integral member including a web portion having openings between the boundaries

of said web portion, said openings being defined by diagonal intersecting members, said members being disposed in planes at right angles to the plane of said web portion, said web portion being provided with flanges at the two sides thereof, which flanges are parallel with one another throughout the major portion of their length, one of said flanges being swedged into adjacency with the flange at the opposite side of said expanded metal structure.

10 Signed at Gary, Indiana, this 14th day of July, 1927.
